PACKAGE OR CARTON OPENER

James P. Bolt, High Point, N. C.

Application June 26, 1936, Serial No. 87,529

2 Claims. (Cl. 229—51)

The invention relates to a package or carton opener and more especially to a cigarette package opening means.

The primary object of the invention is the provision of a device of this character wherein the same is arranged within the cigarette package or carton at one end thereof beneath the sealing flaps of the same so that such package or carton can be conveniently opened at one end thereof for the removal of the contents such as cigarettes packed therein, the device being of novel construction and applied in a novel manner to the package or carton.

Another object of the invention is the provision of a device of this character wherein through a pull loop made from a cord or the like and loosely engaged with a relatively stiff cardboard plate as worn interiorly of a cigarette carton or package, the latter can be readily and quickly opened at one end thereof, without requiring the hand tearing of the package or carton for the opening of the same. The pull loop when pulled upon will cause the plate to completely open one end of the package or carton and thereby expose the contents of the same for the free removal of such contents as for example cigarettes held therein.

A further object of the invention is the provision of a device of this character which is simple in its construction, not requiring any alteration or change in the packaging of cigarettes or the like and enabling the opening of the latter at one end with dispatch and ease, and inexpensive to manufacture and install.

With these and other objects in view, the invention consists in the features of construction, combination and arrangement of parts as will be hereinafter more fully described, illustrated in the accompanying drawing, which disclose the preferred embodiment of the invention and pointed out in the claims hereunto appended.

In the accompanying drawing:

Figure 1 is a perspective view of a package of cigarettes showing the device constructed in accordance with the invention applied for, the package being closed and sealed.

Figure 2 is a perspective view of the package with the end opened by the device.

Figure 3 is a fragmentary vertical longitudinal section through the package showing the end sealed by full lines and by dotted lines opened.

Figure 4 is a perspective view of the device extracted from the package and its position when pulled therefrom.

Figure 5 is a perspective view of the device prior

to the pulling of the same from the package showing the manner of set of the pull loop of such device when confined within the package.

Similar reference characters indicate corresponding parts throughout the several views in the drawing.

Referring to the drawing in detail, A designates generally a package or carton which is conventional in its make-up and has the usual sealed end B constituted by sealing flaps 10, these being folded, overlapped and sealed in the customary or usual manner for the packaging of cigarettes or the like. This sealed end B of the package A as is usual carries the revenue stamp C.

Adapted to fit within the package A is a relatively stiff plate 11 of cardboard or the like, its contour being identical with the cross sectional size of the package A. Such plate is adapted to be disposed interiorly of the package A next to the sealed end B underlying the sealing flaps 10 thereof and of course the revenue stamp C which is externally applied to the said sealed end B.

Trained through spaced holes 12 provided in the plate 11 is a pull loop 13 formed from a single length of cord and such length of cord is knotted at 14. This cord in the loop form 13 is twisted on itself so as to have the stretches 15 criss-crossed when the plate 11 is worn interiorly of the package A and the end B thereof sealed, the stretches 15 of the loop 13 being extended outwardly from between the sealing flaps 10 at opposite ends thereof so that the outer portion of this loop will be outside of the package A. Now to open the package it is only necessary to pull upon the outside or exposed portion of the loop 13 so that stretches 15 thereof will act upon the sealing flaps 10 to break loose the same and for extracting the plate 11 from the package A which causes the sealed end B of this package to become fully opened as is clearly shown in Figure 2 of the drawing, thus giving easy access to the contents of the package A.

Of course, it is understood that when the package A has its sealed end B opened, the plate with the loop 13 loosely passed through the openings 12 in said plate, will be discarded or thrown away.

The plate 11 constitutes a follower on the loop 13 so as to spread the sealing flaps 10 when a pull is had upon the loop 13 and thus the sealed flaps 10 will be caused to open and in this fashion fully opening the sealed end B of the package A when the plate is worn interiorly of the latter.

What is claimed is:

1. The combination of a package having sealing flaps joined with each other and closing the

end thereof, a relatively stiff plate within the package and backing the sealing flaps when joined together and sealing the end of said package, a pull loop engaged with said plate and having a portion exposed exteriorly of the closed end of the package for permitting a manual pull upon the said loop to extract the plate from the closed end and the opening of the latter completely, the said plate being of a shape corresponding to the internal cross-sectional area of the said package and conforming to the closed end thereof, and a cord loosely trained through the plate and constituting the loop with stretches of said cord extended outwardly from between the sealing flaps at the closed end of the package.

2. The combination of a package having sealing flaps joined with each other and closing the end thereof, a relatively stiff plate within the package

and backing the sealing flaps when joined together and sealing the end of said package, a pull loop engaged with said plate and having a portion exposed exteriorly of the closed end of the package for permitting a manual pull upon the said loop to extract the plate from the closed end and the opening of the latter completely, the said plate being of a shape corresponding to the internal cross-sectional area of the said package and conforming to the closed end thereof, and a cord loosely trained through the plate and constituting the loop with stretches of said cord extended outwardly from between the sealing flaps at the closed end of the package, the said stretches of the cord being criss-crossed beneath the sealing flaps of the closed end of the package.
